TELEVISION REMOTE CONTROL OR SIMILAR ARTICLE

John W. Mason, Glenview, Ill.

Application July 1, 1957, Serial No. 46,793

Term of patent 14 years

(Cl. D26—13)

Fig. 1 is a top plan view of a television remote control or similar article, showing my new design;

Figure 2 is a side elevational view, partly broken away and in cross-section, the opposite side having substantially the same appearance;

Figure 3 is a bottom plan view; and

Figure 4 is an end elevational view, the opposite end being conventional.

I claim:

The ornamental design for a television remote control or similar article, as shown and described.
